UNITED STATES PATENT OFFICE

114,996

DESIGN FOR A KITCHEN GAUNTLET

Miriam Gross, Chicago, Ill.

Application April 1, 1939, Serial No. 83,978

Term of patent 14 years

To all whom it may concern:

Be it known that I, Miriam Gross, a citizen of the United States, residing at Chicago, county of Cook, and State of Illinois, have invented a new, original, and ornamental Design for a Kitchen Gauntlet, of which the following is a specification, reference being had to the accompanying drawing, forming a part thereof, in which:

Figure 1 is a plan view of the gauntlet; and
Figure 2 is a side elevational view of the same.

The characteristic feature of the design is that the thumb portion of the gauntlet extends laterally so that the gauntlet may be worn on either hand. The gauntlet is made of soft fabric and is padded or quilted so that it may be used in picking up hot kitchen utensils and the like.

I claim:

The ornamental design for a kitchen gauntlet, as shown and described.

MIRIAM GROSS.
